Invention,
George F. Miller,
By Lyneforth, See Channing Mills,
Attys.

UNITED STATES PATENT OFFICE.

GEORGE F. MILLER, OF DUNNING STATION, ILLINOIS.

SPRING OILER.

Application filed October 20, 1921. Serial No. 509,056.

To all whom it may concern:

Be it known that I, GEORGE F. MILLER, a citizen of the United States, residing at Dunning Station, in the county of Cook and 5 State of Illinois, have invented a new and useful Improvement in Spring Oilers, of which the following is a specification.

My invention relates, more particularly to oiling devices for oiling laminated leaf-springs commonly used for supporting the bodies of vehicles, and more particularly automobile-bodies, on the underframes thereof, to maintain the desired amount of lubricant between adjacent laminations of the 10 springs, this type of device being formed of a body-part adapted to be secured to the side of the spring crosswise of its laminations, with a pad of oil-soaked material interposed between the body-part referred to 15 and the spring-structure.

My object is to provide a novel, simple and economical construction of the character, and for the purpose, above referred to, which will serve in a highly effective manner, to perform its function and be noiseless in the movement of the vehicle and the flexing of the spring.

Referring to the accompanying drawing:—

30 Figure 1 is a broken view in side elevation of a laminated leaf-spring, showing my improved oiling device attached thereto in operative position; and Figure 2, a section taken at the line 2—2 on Fig. 1 and viewed 35 in the direction of the arrow.

The device in accordance with the preferred embodiment of my invention, comprises a cup-shaped body-member 3 of flexible material, preferably leather pressed from 40 a sheet thereof into cup-shape to provide about its, preferably circular, margin, a continuous rim, or flange, 4, the body 3 continuing diametrically-opposed slots 5 adjacent the rim 4. Located within the bottom portion of the cup 3 is a body 6 forming a pad, of any suitable oil-absorbing material such as, for example, wool-felt, which preferably 45 is secured to the cup 3, as by a rivet represented at 7.

50 The bottom, or base portion, of the cup 3 is apertured to permit of the forcing of oil into the body 6 of padding, two such apertures being shown at 8, and containing eyelets 9 the outer ends of which extend beyond 55 the outer surface of the cup 3 and serve to

prevent the apertures 8 from becoming clogged with dirt.

In use the article would be applied to the side of the spring, as for example that shown at 80, the laminations of which are 60 represented at 90, to position it thereon as shown to cause the pad 6 to be held in contact with the side of the spring crosswise of the laminations, and any suitable means employed for securing it in said position, the means shown, and preferably used, comprising a flexible strap 10 as of leather, which extends, at a portion thereof between its ends, across the outer surface of the cup 3, 65 its ends being threaded through the slots 5, one end of the strap carrying a buckle 11, as for example, of common construction, and its opposite end being insertible into the buckle 11 and adapted for interlocking therewith, whereby the device may be 70 strapped to the spring as shown.

The forming of the cup 3 of flexible material, and more particularly leather, is of advantage as the construction not only may be made at low cost, but the parts of the device readily conform to the shape of the particular spring to which it may be applied, and furthermore, and particularly in connection with the employment of the flexible 80 securing means, the device is rendered noiseless in the movement of the vehicle and the 85 flexing of the springs.

While I have illustrated and described a particular embodiment of my invention I do not wish to be understood as limiting it 90 thereto, as the same may be variously modified and altered without departing from the spirit of my invention.

What I claim as new, and desire to secure by Letters Patent, is:

1. A spring oiler formed of a cup-shaped member of flexible non-metallic material for receiving oil-absorbing material.

2. A spring oiler formed of a cup-shaped member of leather for receiving oil-absorbing 100 material.

3. A spring oiler formed of a cup-shaped member of flexible non-metallic material for receiving oil-absorbing material, and means for attaching said member to a spring with 105 said oil-absorbing material in contact with the spring.

4. A spring oiler formed of a cup-shaped member for receiving oil-absorbing material and a flexible non-metallic member engag- 110

ing said cup-shaped member for attaching the latter to the spring.

5. A spring oiler formed of a cup-shaped member of flexible non-metallic material for receiving oil-absorbing material, and a flexible non-metallic member engaging said cup-shaped member for attaching the latter to the spring.

6. A spring oiler formed of a cup-shaped 10 member of flexible non-metallic material and a pad of oil-absorbing material located, and confined, in said member.

7. A spring oiler formed of a cup-shaped member of flexible non-metallic material, a 15 pad of oil-absorbing material located, and confined, in said member, and means for attaching said member to a spring with said pad in contact with the spring.

8. A spring oiler formed of a cup-shaped 20 member, a pad of oil absorbing material located within said cup and secured therein, said cup containing openings at opposite sides of its center, and a flexible member for securing said cup in position on a spring, 25 extending across the outer surface of said cup-shaped member and threaded through said openings.

9. A spring oiler formed of a cup-shaped member of flexible material, a pad of oil-absorbing material located within said cup 30 and secured therein, said cup containing openings at opposite sides of its center, and a flexible member for securing said cup in position on a spring, extending across the outer surface of said cup-shaped member 35 and threaded through said openings.

10. A spring oiler formed of a cup-shaped member for receiving a pad of oil-absorbing material, said cup containing openings at opposite sides of its center, and a flexible 40 member for securing said cup in position on a spring, extending across the outer surface of said cup-shaped member and threaded through said openings.

11. A spring oiler formed of a cup-shaped 45 member of flexible material for receiving a pad of oil-absorbing material, said cup containing openings at opposite sides of its center, and a flexible member for securing said cup in position on a spring, extending across 50 the outer surface of said cup-shaped member and threaded through said openings.

GEORGE F. MILLER.
